DOOR

Robert F. Thompson, 19105 107th Place NE.,
Bothell, Wash.

Filed Mar. 13, 1962, Ser. No. 69,243

Term of patent 14 years

(Cl. D13—1)

FIGURE 1 is a front elevational view of a door showing my new design;

FIG. 2 is a sectional view, with parts in elevation, on a larger scale, and taken substantially on broken line 2—2 of FIG. 1; and

FIG. 3 is a sectional view, with parts in elevation, on the same scale as FIG. 2, and taken substantially on broken line 3—3 of FIG. 1.

The rear of the door is substantially like the front except as indicated in FIGS. 2 and 3.

I claim:

The ornamental design for a door, as shown and described.
